COMBINED HOLDER FOR INDEX PAD AND MEMORANDUM SHEETS

Morton M. Rodbell, New York, N. Y.

Application April 6, 1950, Serial No. 9,019

Term of patent 14 years

(Cl. D74—1)

To all whom it may concern:

Be it known that I, Morton M. Rodbell, a citizen of the United States of America, residing at 545 West End Avenue, in the city, county and State of New York, have invented a new, original, and ornamental Design for a Combined Holder for Index Pad and Memorandum Sheets, of which the following is a specification, reference being had to the accompanying drawing, forming part hereof, in which:

The left side of the unit Figure 1 corresponds exactly to the right side of the unit of Figure 1, and the rear wall of the unit of Figure 1 is plain.

I claim:

The ornamental design for a combined holder for index pad and memorandum sheets, as shown and described.

MORTON M. RODELL.
